UNITED STATES PATENT OFFICE.

JULIUS A. MEYER, OF NEWARK, NEW JERSEY, ASSIGNOR OF ONE-TENTH TO CHARLES G. GRIFFITH, OF NEWARK, NEW JERSEY.

BUTTON.

Application filed May 3, 1926. Serial No. 106,494.

This invention relates to improvements in buttons and the principles of the invention are susceptible of embodiment in buttons for coats and other body garments and also to buttons for collars, shoes, etc.

It is a well known fact that in the use of ordinary buttons such as is applied to a coat or other body garment, the frequent passage of the button through the buttonhole causes considerable wear on the buttonhole and likewise there is considerable strain imposed upon the thread which unites the button to the garment as any twisting of the button in a manner tending to rotate the same causes the walls of the perforations through which the threads are passed, to wear the threads, and likewise, the difficulty which is sometimes experienced in engaging such a button through its buttonhole will result in a pulling strain upon the threads as well as a twisting strain. Therefore, in one embodiment, the invention has as its object to provide a garment button which will overcome these difficulties, and more specifically, the invention contemplates the provision of such a button comprising a shank member which is sewed to the garment, and a body member which is freely rotatable about the shank member, so that the threads which attach the button to the garment will not be subjected to the strains referred to above.

It is also well known that difficulty is frequently experienced in buttoning a collar over the ordinary one-piece collar button and, therefore, another embodiment of the invention contemplates providing a collar button the head of which will be freely rotatable so as to adapt it to be more readily inserted through the buttonhole of the collar.

The invention likewise contemplates the provision of a shoe button, the head of which will be rotatable so that the button will more readily enter the buttonhole and there will be less likelihood of breaking off the head when the button hook is applied thereto and the button is drawn through the buttonhole, and likewise no likelihood of imparting to the shank of the button the strain usually imposed thereon, where, in the manipulation of the button hook there is a tendency for the head to rotate.

In the accompanying drawings:

Figure 1 is a view in front elevation of a

garment button constructed in accordance with the invention.

Figure 2 is a rear view thereof.

Figure 3 is a detail diametric sectional view taken on the line 3-3 of Figure 1, looking in the direction indicated by the arrows.

Figure 4 is a sectional perspective view illustrating a collar button constructed in accordance with the invention.

Figure 5 is a similar view illustrating a shoe button so constructed.

In the embodiment of the invention shown in Figures 1, 2 and 3 of the drawings, the button is of the type adapted for use upon coats and other garments and the same comprises a circular head indicated in general by the numeral 1, and a shank indicated in general by the numeral 2. The head 1 may be of any material found suitable for the purpose and of any desired contour and ornamented in any manner desired, and this head is, as usual, slightly convex at its rear side, as indicated by the numeral 3, and somewhat concave at its front, the head being formed centrally with an opening 4 instead of with the usual perforations for the passage of the threads which ordinarily unite the button to the garment to which it is applied. The opening 4 is of general circular contour and its wall is slightly rounded as at 5, at the rear face 3 of the button and likewise, the opening is slightly flared, as at 6, at its end which is presented at the face of the button.

The shank 2 of the button is preferably of metal and the same comprises a central body portion indicated by the numeral 7, which is formed with a plurality of perforations 8 through which the securing threads may be drawn in attaching the shank to the garment. The body of the shank is exteriorly of a diameter to fit within the opening 4 and in assembling the shank and the head of the button, the shank is disposed within the opening 4 and the rim of the shank, which rim is indicated by the numeral 9 and is formed by recessing the forward end of the body of the shank, as indicated by the numeral 10, is overturned in an outward direction so as to engage the flared end 6 of the wall of the opening 4. The body of the shank is provided at its rear side with a circumferential flange 11, the outer

or rear surface of which is preferably rounded and smooth, as indicated by the numeral 12, the said flange having its forward side somewhat concave so as to engage 5 against the convex rear side 3 of the head of the button. It will now be evident, and particularly by reference to Figure 3 of the drawings, that the head of the button is retained upon the shank through its engagement 10 between the overturned rim 9 of the shank body and the flange 11 and at the same time, the head is free to rotate about the shank. The button is applied by sewing the shank to the garment and it will 15 be evident that inasmuch as the head of the button is freely rotatable, it may be engaged through its buttonhole without the wear which is usually imposed upon the buttonhole where the button is not rotatable. It 20 will likewise be evident that if there is any slight distortion of the garment which would ordinarily cause a twisting of the head of the ordinary button, in this instance the head of the button is rotatable so that no 25 strain is imposed upon the threads which secure the shank to the garment. It will likewise be evident that the thickness of the flange 11 permits of the button being united to the garment with its rear side fitting directly 30 snugly against the garment whereas in the case of the ordinary button, the securing threads must be so stitched as to permit of slight spacing of the button. Therefore, in the present invention, the buttonhole does not necessarily contact the threads by which the button is secured to the garment so that the threads are not subjected 35 to the wear which ordinarily results from such frictional contact with the walls 40 of the buttonhole. Of course, the shank member 2, while of metal, may be enameled to correspond with the finish of the head of the button, or it may be artistically finished as desired, and it may indeed be found 45 desirable to employ some material other than metal in the manufacture of this part of the button. However, in any event, the head of the button will be rotatable upon the shank member so that the advantages 50 heretofore outlined will be obtained.

In Figure 4, which illustrates the principles of the invention embodied in a collar button, the shank of the button is indicated by the numeral 13 and is provided with an integral back which is preferably of circular form as indicated by the numeral 14. The shank is reduced in diameter so as to provide a shoulder 15, and a cylindrical reduced portion 16, and the head of the button, 55 which is indicated by the numeral 17, is formed centrally or axially with an opening 18 to accommodate the said reduced portion 16, the end of the reduced portion being headed as indicated by the numeral 19, so 60 as to retain the head 17 in place upon the

reduced portion 16 between the headed end 19 and the shoulder 15 and yet permit of free rotation of the head about the portion of the shank upon which it is mounted. In this embodiment, the shank member and the 70 head may be formed of any material found suitable for the purpose and it will be evident that a button thus constructed will present advantages over the ordinary collar button in that the collar may be buttoned 75 over the button without likelihood of mutilating the buttonhole of the collar and likewise in a more ready manner than in the use of the ordinary button.

In Figure 5 of the drawings, the invention is illustrated as embodied in a shoe button having a shank member 20 one end of which is bent to provide an attaching eye 21 not unlike the eye of the shank of an ordinary shoe button. However, in accordance with the invention, the head of the button, which is indicated by the numeral 22, is rotatably fitted upon the main or straight portion of the shank, indicated by the numeral 23, so that it will rotate freely 85 thereon between the eye 21 and the outer end of the said shank portion 23, which latter is headed as at 24, so as to retain the head 22 in place. In the use of such a button, all of the advantages outlined for the 90 previously described form are obtained and likewise it will be evident that when a button hook is engaged with the head of the button shown in Figure 5, the head will rotate in consonance with the movement given 100 to the button hook so that no strain is imposed on the shank member tending to twist the same loose from the shoe.

Having thus described the invention, what I claim is:

A button comprising a head formed with a circular shank receiving opening having convexed walls arcuate in cross section and increasing in diameter toward its forward end, and a shank member including a body portion circular in cross section and fitting into the opening of said head, the body being formed with fastener receiving openings, an annular flange projecting radially from the inner end of said shank in overlapping relation to the head and having close contacting engagement with the inner face thereof about its shank receiving opening, the forward end portion of said body being recessed to form a circumferentially extending rim tapered to a feather edge and flared outwardly into close fitting engagement with the walls of the enlarged forward end portion of the shank receiving opening of the head whereby the body will be freely 110 rotatable upon the shank and held against movement longitudinally thereon.

In testimony whereof I affix my signature.

JULIUS A. MEYER. [L.S.]
